ATTORNEY

UNITED STATES PATENT OFFICE

JULIUS WEINBERGER, OF NEW YORK, N. Y., ASSIGNOR TO RADIO CORPORATION OF AMERICA, A CORPORATION OF DELAWARE

DESIGN FOR A RADIO RECEIVER CONTROL

Application filed December 6, 1929. Serial No. 33,670. Term of patent 7 years.

To all whom it may concern:

Be it known that I, JULIUS WEINBERGER, a citizen of the United States, and resident of New York city, New York, have invented a certain new, original, and ornamental Design for a Radio Receiver Control, of which the following is a specification, reference being had to the accompanying drawing, forming part thereof.

Fig. 1 of the drawing is a front view of a radio receiver control showing my new design,

Fig. 2 is a side view thereof.

I claim:

The ornamental design for a radio receiver control substantially as shown.

JULIUS WEINBERGER.
